(57) **CLAIM**

We claim the ornamental design for a shears, as shown and described.

DESCRIPTION

FIG. 1 is a top perspective view of the claimed design;

FIG. 2 is front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines represent portions of the shears and form no part of the claimed design.
